UNITED STATES PATENT OFFICE.

PATRICK J. ENRIGHT, OF SAN FRANCISCO, CALIFORNIA.

RADIATOR-BRACKET.

1,184,435.

Specification of Letters Patent.

Patented May 23, 1916.

Application filed September 8, 1913. Serial No. 788,762.

To all whom it may concern:

Be it known that I, PATRICK J. ENRIGHT, a citizen of the United States, residing in the city and county of San Francisco, State of California, have invented certain new and useful Improvements in Radiator-Brackets, whereof the following is a specification.

This invention relates to brackets for supporting steam and hot water radiators and similar appliances.

In carrying out the invention I construct a bracket which comprises a wall plate adapted to be attached to a wall or similar structure; an arm for the radiator to rest upon, which arm projects from the lower part of the wall plate; and a slotted arm projecting from the upper part of the wall plate, and adapted to receive a bolt. The invention also comprises, in combination with such bracket, a bolt adapted to engage the bracket and provided with a button adapted to engage the radiator.

In the accompanying one sheet of drawing I have illustrated the specific form of my invention which I consider the best.

In the drawing: Figure 1 is a sectional elevation showing part of a wall, the bracket attached thereto, and a radiator in place supported by the bracket. Fig. 2 is a front elevation of the bracket. Fig. 3 is a horizontal section showing the same parts shown in Fig. 1, taken at the line 3, 3, on Fig. 1.

In these figures the wall is represented at 1, the bracket A being attached thereto by screws at 2, 2, passing through the wall plate 3. The bracket A comprises the wall plate 3, and the arms 4 and 5. The arm 4 at the lower end of the wall plate is shaped to fit the under surface of the radiator 6, which rests thereon. The arm 5, at the upper end of the wall plate, is formed with an inverted T-shaped slot, 8, therein, to provide means for adjustably holding a bolt 7, the head or nut thereof resting in a space 9 back of the slotted portion and engaging the edges thereof. The bolt 7 is provided with a nut 10 at one end and a head 11 at the other, the head being preferably slotted to receive a screw-driver.

50 12 is a cone shaped button applied to the bolt, being perforated for the passage thereof. This button is adapted to engage the upright members 13 of the radiator 6 and hold the same in position upon arm 4.

55 The apparatus, as thus constructed, will

support and secure radiators of a variety of sizes and shapes, and will also accommodate, by the adjustment of the bolt in the slot, variations or imperfections in the radiators and in the placing of the brackets. 60

Having thus described my invention and believing I have produced useful and novel improvements in the art to which it appertains let it be understood that I do not wish to be limited to the exact construction 65 and arrangement of the several parts composing the same, as many changes can be made without departing from the spirit thereof, but

What I claim and desire to secure by 70 United States Letters-Patent is:

1. A radiator bracket comprising a wall plate projecting outwardly at its lower and upper ends, the lower end forming a fixed supporting arm engaging the under side of 75 a radiator and supporting the same in position, the upper projecting end being provided with a vertical and horizontal slot, a bolt adjustably mounted in said slots, a nut on said bolt and means for holding said nut 80 in position.

2. A radiator bracket comprising a wall plate projecting outwardly at its lower and upper ends, the lower projecting end being adapted to support said radiator in vertical 85 position, the upper projecting end being provided with inverted T shaped slot and an adjustable bolt provided with a nut engaging said slot and adapted to hold said radiator in position upon said supporting 90 arm.

3. A radiator bracket, comprising a wall plate projecting outwardly at its lower end to form a rigid supporting arm adapted to engage the under side of a radiator, an integral outward projection at the upper part of the wall plate provided with inverted T-shaped slot adapted to adjustably engage a bolt therein, in combination with such bolt, and a cone-shaped button strung on 100 the bolt.

In testimony that I claim the foregoing I have hereto set my hand in the presence of witnesses, this twenty-ninth day of August, 1913.

PATRICK J. ENRIGHT.
